UNITED STATES PATENT OFFICE.

ALFREDE C. LAMAR, OF ST. PAUL, MINNESOTA.

FLAX-PULLER.

SPECIFICATION forming part of Letters Patent No. 566,403, dated August 25, 1896.

Application filed November 19, 1894. Serial No. 529,232. (No model.)

To all whom it may concern:

Be it known that I, ALFREDE C. LAMAR, of St. Paul, in the county of Ramsey and State of Minnesota, have made certain new and useful Improvements in Flax-Pullers, of which the following is a specification.

This invention relates to flax-pullers; and it consists in the construction, combination, and arrangement of parts, as hereinafter shown and described, and specifically pointed out in claims.

Figure 1 is a plan view of the machine with the upper part of the frame removed, and Fig. 2 is a side elevation from the drive side. Fig. 3 is an enlarged plan view of the cam-plate and one of the sets of gripping and pulling devices, illustrating the construction more fully. Fig. 4 is an enlarged detail of the trip-cam by which the gripping-jaws are protruded. Fig. 5 is an enlarged detail of one of the sliding frames of the gripping-jaw mechanism. Fig. 6 is a detached plan view, and Fig. 7 is a detached side view, of the tripping-lever of the gripping-jaws. Fig. 8 is a detached side view of the spring-bolt of the gripping-jaw mechanism. Fig. 9 is an enlarged detail of the gathering mechanism.

A' is the base-frame, and A^2 the upper frame, supporting an upright central shaft B' between them, the two parts of the frame formed and connected in any suitable manner to withstand the severe strains to which they will be subjected. Upon one side the frame A' is supported by the main driving-wheel D' , the axle D^2 of the latter provided with a pinion D^3 , loose upon the axle and engaging with a segmental rack D^4 , fast on the frame A' , as shown in Fig. 2, the revolution of the pinion serving to elevate and depress the frame A' , as hereinafter explained.

E' is a horizontal shaft journaled upon the frame A' and having a chain-sheave E^2 , adapted to be driven by a chain E^3 from a chain-sheave E^4 on the axle D^2 of the wheel D' , the revolution of the wheel D' thus imparting motion to the shaft E' in the usual manner of harvesting-machines. The shaft E' thus becomes the center upon which the frame $A' A^2$ moves when elevated and depressed by the gearing $D^3 D^4$. Upon the inner end of the shaft E' is a bevel-pinion E^5 , engaging with a corresponding bevel-pinion E^6 on an up-

right shaft E^7 , suitably supported from the frame $A' A^2$ and having a chain-sheave E^8 on its upper end adapted to revolve the shaft B' by a chain E^9 and chain-sheave B^2 , whereby the requisite rotary motion is imparted to the shaft B' and its attachments. A clutch E^{10} is connected into the shaft E' between the chain-sheave E^8 and gears $E^5 E^6$ and adapted to be actuated by a lever E'' , convenient to the hand of the operator, whereby the mechanism may be thrown in and out of gear when moving from place to place or for any other purpose.

$F' F^2$ are two caster-wheels, one at the front and one at the rear of the machine, about in line with the side of the frame $A' A^2$ opposite to the wheel D' , the supporting swivel or caster frames $F^3 F^4$ each having an upright shaft or stud $F^5 F^6$ passing through bearings $F^7 F^8$ on the ends of the extended sections $A^3 A^4$ of the upper frame A^2 , as shown, the studs $F^5 F^6$ being loose in the bearings and free to be moved vertically and revolve in the bearings. The bearings $F^7 F^8$ are formed with jaws $a' a^2$ and support arms $F^9 F^{10}$ between the two parts of the jaws, the arms being slidable upon the studs $F^5 F^6$, but prevented from turning thereon by feather-keys $a^3 a^4$ fitting into vertical grooves $a^3 a^4$ in the studs.

G' is the tongue-socket, fast to the front of the frame in which the tongue G^2 is secured. A vertical post or standard G^3 rises from the socket G' and is provided on its upper end with two arms $G^4 G^5$, the arm G^4 being connected by rod G^6 to the arm F^9 , and the arm G^5 being connected by rod G^7 to the arm F^{10} , as shown. By this arrangement when the tongue is "cramped" to one side the arms $G^4 G^5$ move with it, and by being connected by the arms $F^9 F^{10}$ the caster-wheels are turned to correspond, so that the machine will "track" properly and the caster-wheels retained at all times in proper relations to the wheel D' and tongue G^2 . Journaled to each of the bearings $F^7 F^8$ is a chain-pulley $b' b^2$, underneath which chains $b^{15} b^{16}$ pass from collars $b^3 b^4$ on the studs $F^5 F^6$ to and over chain-pulleys $b^5 b^6$ on the frame A' , and thence to the shackle b^7 , carrying another chain-pulley, b^8 . Another chain, b^{10} , is arranged to pass from a point b^9 on the frame A' to and around the pulley b^8 , and thence to a drum

b^{11} on the frame A' , as shown. This drum b^{11} is adapted to be revolved by a lever b^{12} , having holding-pawls $b^{13} b^{14}$, as shown, whereby the chain may be wound upon the 5 drum or unwound therefrom, as required. The frame $A' A^2 A^3 A^4$ and all of its attachments are thus suspended upon the studs $F^5 F^6$ by the chains $b^{15} b^{16}$ and adapted to be elevated and depressed and held at any required point of elevation by revolving the 10 drum b^{11} forward or backward. The pulley b^8 and chain b^{10} serve as an equalizer to enable both ends of the frame $A' A^2$ to be actuated together, and also to enable both 15 chains $b^{15} b^{16}$ to be actuated by one chain only from the drum b^{11} . Another chain, b^{17} , passes from the drum b^{11} to and over a pulley b^{18} on the frame A' , and thence downward and around a pulley b^{19} on the lower part of the 20 frame A' in a position below the line of the lowest point to which the axle D^2 of the wheel D' will be moved, and thence to and around a drum on the axle to which its other end is secured. By this means the wheel D' is suspended 25 wholly by the bight of the chain b^{17} , and when the drum b^{11} is revolved the axle D^2 will likewise be revolved and cause the pinion D^3 to revolve in the rack D^4 , and thus elevate or depress the side of the frame next 30 to the driving-wheel at the same time and to the same extent as the side next to the caster-wheels. Thus the whole frame is uniformly elevated and depressed by revolving the one drum b^{11} and by one lever b^{12} .

35 B^3 is a "spider" secured to the shaft B' and having a series of guides B^4 radiating therefrom and at equal distances apart, the guides being attached at their outer ends to a ring B^5 , as shown in Fig. 1. The guides are formed 40 with parallel sides, and any required number may be employed. For the purpose of illustrating I have shown five of these guides, but in practice a larger number, usually thirteen, will be employed. Within each of these 45 guides B^4 a frame B^6 is arranged to be moved inward and outward, its edges fitting into suitable grooves in the inner edges of the guides. Near their outer ends each of these 50 frames B^6 is provided with a curved slot d' , in which a roller d^2 on an arm d^3 fits, the outer end of the arm being pivoted at d^4 to the side of guide B^4 . Each of the arms d^3 is formed 55 with shorter arms $d^5 d^6$ and each of the shorter arms provided with an antifriction-roller $d^7 d^8$. By this arrangement any force brought to bear upon the rollers $d^7 d^8$ will oscillate the lever d^3 upon its pivot and move the sliding frame B^6 inward or outward between the sides of the guides B^4 , as will be 60 more readily understood by reference to the large detail Fig. 5. Journaled by studs $e' e^2$ upon the outer ends of each of the frames B^6 are small gear-segments $e^3 e^4$, adapted to engage with each other, and the segment e^4 , adapted to be likewise engaged by another 65 segment e^5 , the latter journaled by a stud e^6 on the frame B^4 and having an arm e^7 pivoted

at e^8 to one end of a spring-rod e^9 , as shown. The other end of this spring-rod is pivoted to the outer end of an arm e^{10} , journaled by a 70 stud e^{11} on the frame B^6 , as shown. Attached centrally to the lower end of this stud e^{11} , beneath the frame B^6 and guides B^4 , is an arm e^{12} , having antifriction-rollers $e^{13} e^{14}$ upon its ends, as shown more clearly in Fig. 6. Projecting from the segments $e^3 e^4$ are arms $e^{15} e^{16}$, 75 curved in opposite directions and forming the gripping-jaws, as hereinafter shown. By this arrangement if the arm e^{12} be turned in one direction the arms e^{10} through the spring-rod e^9 will likewise oscillate the segments $e^3 e^4 e^5$ and cause the jaws $e^{15} e^{16}$ to assume the position shown at the left in Figs. 1 and 3, or assume the position shown at the right in Fig. 1, when the arm e^{12} is turned in the opposite direction, as hereinafter more fully explained. Connected by small rods $e^{17} e^{18}$, between each pair of the jaws $e^{15} e^{16}$, is a 80 reversely-curved bar e^{19} , the outer ends of the rods $e^{17} e^{18}$ being pivoted to the arms $e^{15} e^{16}$ 85 outside of the segments $e^3 e^4$, as shown, so that when the segments are turned toward each other, as at the right in Fig. 1, the curved bar will be projected outward to reduce the area of the space inclosed by the converging jaws $e^{15} e^{16}$ 90 and assist in the compression of the material inclosed by them, and also to prevent the material coming in contact with the segments or other mechanism.

H' is a horizontal shaft journaled to the 100 frame A' and at an angle to the line of travel of the machine, and adapted to be driven by a shaft H^2 and gears $H^3 H^4 H^5 H^6$ from the main driving-shaft E' , as shown in Fig. 1. Upon this shaft H' are mounted a series of 105 chain-sheaves H^7 , from which endless chains H^8 lead to and around other chain-sheaves H^9 , the shafts of these chain-sheaves H^9 being journaled as near the ring B^5 as possible, the chains being therefore of unequal lengths, as 110 shown. At suitable intervals spurs g are attached to the chains to form carriers to conduct the gavels of pulled flax into the receiver H^{10} , as hereinafter described. The spaces between the chains will be filled with strips of 115 sheet metal to support the gavel; but these are not shown, as they would obstruct the view of the machinery.

K is a lever pivoted at h' to the frame A' and provided with fingers h^2 on one end and connected by a rod h^3 from its other end to a crank h^4 , the latter adapted to be revolved rapidly by gears $h^5 h^6$ from the shaft H' . By this means the fingers h^2 are rapidly agitated to strike the roots of the gavels of pulled flax 120 as they are carried past them to remove the earth adhering thereto.

L' is a guard-arm supported by arms $L^2 L^3$ (shown only by dotted lines in Fig. 1) from the frame A' in position parallel to the line 130 of travel of the machine and with the rear end L^4 carried upward and backward and united to the extension A^3 at a point near the bearing F^7 , as shown. Pivoted at i to the for-

ward end of the arm L' is a dividing-finger L^5 , curving outward and adapted to divide the flax and divert the proper quantity into the space between the bar L' and frame A' .

5 m' is a short shaft journaled upon the bar L^4 and having an arm m^2 connected by a rod m^3 to the guard-finger L^5 in advance of its pivot i .

m^5 is a rod extending from the shaft m' 10 backward and upward and through an eye m^6 on the collar b^3 on the stud F^5 , as shown. By this arrangement when the frame $A' A^2$ is lowered down, as it will be when short flax is to be pulled, the shaft m' will be lowered with 15 it, while the eye m^6 , remaining always at the same height, will hold the upper end of the rod m^5 upward, and thus turn the shaft m' in its bearing and cause the arm m^2 to move the outer point of the jointed finger L^5 outward, and thus increase the area of the flax which it will inclose and compress, or, in other words, increase the width of the "swath" harvested. If, however, the frame $A' A^2$ be elevated, as it will be when long or tall flax 25 is to be harvested, the outer point of the divider-arm L^5 will be drawn inward to decrease the width of the swath harvested by the machine. Thus the machine automatically adapts itself to the work required and the 30 condition of the crop being harvested.

Pivoted at n' to the frame A' is a lever M' , connected by a rod M^2 to a trip-lever M^3 , pivoted at n^4 to the frame A' , the inner curved end 35 of the lever M' adapted to be acted upon by each of the rollers d^7 , as the spider B^3 and its attachments are revolved, to throw the inner end of the arm M' forward behind the advancing gavel to gather the loose stalks which the jaws $e^{15} e^{16}$ may have missed, and holding 40 them back so that the next set of jaws may inclose them.

Pivoted at n^2 upon the bar L' , opposite the pivot n' , is another arm, M^4 , similar to the arm M^3 and connected by rod M^5 to another arm, 45 M^6 , the latter pivoted at n^3 and curving inward, as shown, toward the frame A' and ring B^5 and adapted to be acted upon by the second advancing gavel to cause the inner end 50 of the arm M^4 to be moved forward behind the first gavel and coat with the arm M^3 to gather the loose stalks, which the jaws $e^{15} e^{16}$ may fail to inclose, and hold them back, so that the 55 next set of jaws may inclose them, as herein-after described. Secured to the frame A' beneath the spider B^3 and its attached guides B^4 are a series of cam-ribs, formed as shown more clearly in Fig. 3. The ribs may be connected to or formed upon a plate and the plate attached to the frame A' , or each separate rib attached to the frame, as preferred. The cam-rib consists principally of three main ribs $N' N^2 N^3$, concentrically curved 60 with relation to the central shaft B' , that is to say, the rib N' from t' to t^2 is concentric to the shaft B' , the rib N^2 from t^3 to t^4 is concentric to the same shaft, but of a less radius than the rib N' , while the rib N^3 from

t^5 to t^6 is concentric to the shaft B' , but of a less radius than the rib N^2 , as shown more clearly in Fig. 3. From the point t' an inwardly-branching rib N^4 runs, the outer end being curved, as at t^7 , where it unites with the rib N' . At the other end of the section N' a rib N^5 runs in an inwardly-curved line from t^2 to t^8 , while another extension, N^6 , runs inward from t^8 to t^9 . From the point t^4 an extension N^7 runs outward to a point t^{10} , and thence in an outwardly and then in an inwardly curving line to a point t^{11} nearly opposite the point t^7 , the central point t^{12} being the farthest from the central shaft. Within the space inclosed between the portion N^5 and N^7 a smaller rib N^8 is formed, as shown. Outside of the rib-section N^7 is a short rib N^9 , concentric to the shaft B' and rib-section N' and 85 having outwardly-curving ends $t^{13} t^{14}$.

Attached to the frame A' , at a point a little behind the point t' , is a trip mechanism, consisting of a short rib N^{10} , concentric to the shaft B' and in the path of the roller d^7 , this 90 cam-rib being adapted to actuate the arm d^3 and move the sliding frames B^6 outward, one after the other, as they are revolved against it. Upon one end of the rib N^{10} another rib N^{11} is hinged and supported by a spring N^{12} 95 to receive the first impact of the roller d^7 , the spring permitting the rib to yield, so as to lessen the force of the blow. A short guard-rib N^{13} is also arranged in front of the rib N^{11} to assist in guiding the roller into its 100 proper place. Pivoted at t^{15} in front of the curved portion t^7 (the pivot t^{15} being the center from which the curve t^7 is struck) is a short rib N^{14} , made yielding by a spring N^{15} and resting in a slot in the end of the rib N^8 . 105 From the point t^3 the rib N^2 projects outward for a short distance to a point t^{16} , as shown. These different forms and configurations of the cam-ribs and trips serve to act upon the rollers $d^7 d^8 e^{13} e^{14}$ to cause the jaws $e^{15} e^{16}$ to 110 be projected outward against the mass of flax inclosed by the finger L^5 and bar L' , as shown at the left in Fig. 1, and then be compressed around the gavel thus inclosed, as at the right in Fig. 1, and be moved around as the machine advances to pull the flax-roots out of the ground and carry the roots over the rapidly-vibrating fingers h^2 , where the earth is removed, and thence laying the gavel upon the chains H^8 , where it is caught by the spurs 115 g and carried thence into the receiver H^{10} , the jaws $e^{15} e^{16}$ being distended and withdrawn at the point when the gavel is laid over the endless chains. These different motions are produced as follows: When the revolving 120 frame B^3 is carrying the guides B^4 from the point $t^4 t^6$ to $t^5 t^8$, the rollers $e^{13} e^{14}$ will be on opposite sides of the rib-section N^8 , as shown in Fig. 3, and the pulling mechanism held in its inward position and the jaws $e^{15} e^{16}$ open, 125 as shown. Then when the roller d^7 strikes the spring-section N^{10} the latter yields somewhat and receives the first impact of the blow to prevent breakage, and then the roller

*d*⁷ is moved inward by the fixed rib-section N¹⁰, this motion moving the arm d³ outward and carrying the frame B⁶ outward by the action of the roller d² in the slot d', thus also carrying the distended jaws e¹⁵ e¹⁶ outward into the mass of flax gathered between the finger L⁵ and bar L' and the frame A', but without closing the jaws, as the rollers e¹³ e¹⁴ have not as yet been affected, but have simply run outward, one on each side of the rib N¹⁴, the latter serving to prevent the arm e¹² from being turned prematurely. When the roller e¹³ first comes against the rib-section N¹⁴, the impact is considerable, and to prevent damage the rib-section is provided with the spring N¹⁵ to cause the section to yield under this pressure.

During the outward movement of the frame B⁶ the roller e¹⁴ runs in close proximity or in direct contact with the section N⁴, and when it reaches the curved portion t' the roller is retarded thereby and held back to a sufficient extent to turn the arm e¹² on its pivot e¹¹, and thus throw the arm e¹² and rod e⁹ outward and revolve the segments e⁵ e⁴ e³, and thus converge the jaws e¹⁵ e¹⁶ and compress the flax between them, the curved arm e¹⁹ being at the same time forced outward, as before described, to increase the pressure.

As the spider-frame and its attachments continue to revolve, the roller e¹⁴ runs around the end t' of the cam-rib N' and is carried around in this position until the point t' is reached. The cam-rib N' being concentric to the shaft B' from t' to t², the jaws e¹⁵ e¹⁶, while passing that portion, will be held uniformly in their closed relation, and will thus retain the gavel firmly in their grip. While thus firmly held, the roots of the gavel are drawn over the rapidly-vibrating fingers h², and the loose earth thereby shaken loose, as before described. As the gavel is carried over the chains H⁸ it is laid over them into a horizontal position, the rollers e¹³ e¹⁴ passing on opposite sides of the cam-section N⁸, which is formed to turn the arm e¹² upon its pivot e¹¹ into its reverse position to reverse the position of the segments e³ e⁴ e⁵ and open the jaws e¹⁵ e¹⁶ and release the gavel. At the same time that the rollers e¹³ e¹⁴ are acted upon by the cam-section N⁸ the roller d⁸ comes in contact with the outer end t¹¹ of the cam-section N⁷ and follows it around to the point t⁴, and is thereby moved inward, turning the arm d³ inward and moving the frame B⁶ to its inward position, as before, and thus withdrawing the open jaws and placing them into the position shown in Fig. 3, the rollers e¹³ e¹⁴ in the meantime having moved inward between the sections N⁶ N⁷ and assumed the position shown in Fig. 3, with one roller on each side of the section N³. As before stated, the cam-sections N² N³ from the points t³ to t⁴ and from t⁵ to t⁶ are concentric to the shaft B'. Hence while the rollers e¹³ e¹⁴ are traveling over these sections the jaws e¹⁵ e¹⁶ will be held uniformly in their inward position

and open. The guides B⁴ will be placed in sufficiently close proximity and the speed of the spider-frame and its attachments will be sufficiently rapid to cause the jaws e¹⁵ e¹⁶, when projected, to grasp all the flax gathered in by the gathering-arm L⁵. Under the same conditions, however, some of the loose stalks may escape the jaws e¹⁵ e¹⁶, and to insure the gathering of these is the function of the arms M³ M⁴, the arms M³ being moved backward by each of the advancing rollers d⁷ in turn, while the arm M⁴ is similarly moved backward by the pressure of the next forward-advancing gavel upon the arm M⁶, and then when the gavels pass the ends of the arms the springs n⁵ n⁶ cause the free inner ends of the arms M³ M⁴ to close again and run in contact with the rear side of the compressed gavel, and thus gather all the loose ungathered stalks and hold them back until the next pair of arms e¹⁵ e¹⁶ inclose them.

By this simple device every stalk of the flax will be gathered.

Having thus described my invention, what I claim as new is—

1. In a flax-pulling machine, the combination of a wheel-frame, a revolving frame carried thereby, a series of oppositely-curved gripping-jaws carried by said revolving frame, means for projecting said jaws outward and closing them to receive a gavel of flax, means for opening said jaws to discharge said gavel therefrom, and drawing the jaws inward again, means for raising and lowering said machine to adapt it to the length of the flax, and a movable divider-arm adapted to be adjusted laterally by the raising and lowering of said machine, whereby the width of the swath to be harvested may be increased or diminished according to the height of the grain, substantially as described and for the purpose set forth.

2. In a flax-pulling machine, the combination with a wheel-frame, of a stationary cam-frame arranged upon said wheeled frame, a revolving frame arranged above said cam-frame and carrying a series of oppositely-curved gripping-jaws, means for projecting said jaws outward and closing them at one point in the movement of said revolving frame, means for opening said gripping-jaws and withdrawing them at another point in the revolution of said frame, means for raising and lowering said wheeled frame and the mechanism supported thereby to adapt the machine to the length of the flax, and a movable divider-arm arranged to be adjusted laterally by the raising and lowering of said frame, whereby the width of the swath is varied in proportion to the height of the grain to be harvested, substantially as described.

3. In a flax-pulling machine, a base-frame adapted to be moved forward, a revolving frame carrying a series of oppositely-curved gripping-jaws, means for projecting said jaws outwardly and closing them to seize a gavel of flax, and means for opening said jaws to dis-

- charge said gavel therefrom and drawing the jaws inward again, an arm projecting into the path of the revolving frame whereby the ungathered stalks are retarded and held into the 5 path of the next set of gripping-jaws, substantially as and for the purpose set forth.
4. In a flax-pulling machine, a base-frame adapted to be moved forward, a revolving frame carrying a series of oppositely-curved 10 gripping-jaws, means for projecting said jaws outwardly and closing them to seize a gavel of flax, and means for opening said jaws to discharge said gavel therefrom and drawing the jaws inward again, an arm projecting into the 15 path of the gavel, a trip-lever connected to said arm projecting into the path of the revolving frame, a secondary reversely-pivoted arm projecting into the path of the gavel from the opposite side, and a curved compressor- 20 lever connected to said secondary arm and adapted to be actuated whereby the ungathered stalks are held into the path of the next set of gripping-jaws, substantially as, and for the purpose set forth.
- 25 5. In a machine of the class described, the combination of the wheeled frame, a second frame carried by said wheeled frame, and provided with a series of curved gripping-jaws arranged in position to engage the flax 30 as the machine is drawn forward, means for closing said jaws, means for drawing said jaws inward and opening them to discharge the flax therefrom, a suitable mechanism for raising and lowering said frame together with 35 said gripping-jaws, and a divider-arm for regulating the width of the swath and arranged to be raised or lowered simultaneously with said frame, substantially as described.
- 40 6. In a flax-pulling machine, the combination with the wheeled frame, of a secondary frame provided thereon and vertically movable, flax-gathering devices provided upon said secondary frame, a dividing-arm to direct the flax toward said gathering devices, 45 and means for adjusting said dividing-arm with respect to said secondary frame, substantially as described.
- 45 7. In a flax-pulling machine, a fixed cam-frame, a frame revolving above said cam-frame and having radiating guides, slidable frames between said guides, oppositely-curved gripping-jaws pivoted to said slidable frames, levers having antifriction-rollers and pivoted to said revolving frame and adapted 55 to project and withdraw said slidable frames, a yielding cam-rib in the path of the rollers upon said levers and adapted to actuate them to project said slidable frames and gripping-jaws, and a cam-section in the path of said 60 rollers upon said lever adapted to actuate them, and withdraw said slidable frames and gripping-jaws, substantially as and for the purpose set forth.
- 65 8. In a flax-pulling machine, a fixed cam-frame, a revolving frame above said cam-frame and having radiating guides, a slidable frame between said guides, oppositely-curved
- gripping-jaws pivoted to said slidable frame and provided upon their pivoted ends with gear-segments in engagement with each other, 70 a pivoted arm or lever having antifriction-rollers and arranged to project and withdraw said slidable frame, a lever or arm having a gear-segment in engagement with one of said gripping-jaw segments, an arm pivoted to 75 said slidable frame and connected by said spring-rod to said lever or arm, an arm or lever pivoted centrally upon said pivoted arm and provided with antifriction-rollers upon its ends and adapted to be actuated by said 80 cam-frame to open and close said gripping-jaws, and a yielding cam-section at the point where said slidable frames are projected, to receive the impact of said antifriction-rollers and thereby prevent breakage, substantially 85 as described.
- 90 9. In a flax-pulling machine, a frame adapted to be moved forward, a revolving frame carrying a series of oppositely-curved gripping-jaws, means for projecting said jaws outward, and closing them to seize a gavel of flax, and means for opening said jaws outward to discharge said gavel therefrom, and drawing the jaws inward again, and a series 95 of endless chains having projected studs, and over which the gavels are laid when the gripping-jaws are withdrawn, and discharged thereby into a receptacle, substantially as and for the purpose set forth.
- 100 10. The combination in a flax-pulling machine, of a wheeled frame with a secondary frame provided thereon and vertically movable, flax-gathering devices operative upon said secondary frame, a dividing-arm laterally adjustable with respect to said gathering devices, and means whereby said gathering-arm is automatically and proportionally adjusted when said secondary frame is raised or lowered and with respect to the position of said secondary frame, substantially as described.
- 105 11. The combination in a flax-pulling machine, of a suitable carrying-frame with a secondary frame provided thereon, flax-gathering devices provided upon said secondary frame and horizontally movable, means for 115 causing said gathering devices to grasp and then discharge a gavel of flax, means for receiving flax from said pulling devices and ejecting the same from the machine, and a dividing or directing arm or device, said secondary frame and the dividing-arm being 120 proportionally adjustable, as and for the purpose specified.
- 125 12. In a machine of the class described, the combination with the wheeled frame having a substantially vertical axis, a revolving frame carried by said wheeled frame, said revolving frame being provided with a series of gripping-jaws, means for closing said jaws to receive a gavel of flax, means for opening said 130 jaws to discharge the flax therefrom, and a suitable mechanism for raising and lowering said revolving frame, as and for the purpose set forth.

13. In a machine of the class described, the combination of the wheeled frame, a second frame having a substantially vertical axis carried by said wheeled frame and provided with a series of gripping-jaws arranged to engage the flax as the machine is drawn along, means for closing said jaws, and means for drawing them inward and opening them to discharge the flax therefrom, and a suitable mechanism for raising or lowering said second frame together with said gripping-jaws, for the purpose set forth.

14. In a machine of the class described, the combination with a suitable wheeled frame, a revolving frame carried thereby, said revolving frame being provided with a series of opposite gripping jaws or parts, said jaws being in position to engage the flax as said machine is moved along, means for closing said jaws to seize a gavel of flax, means for opening the same to discharge the flax therefrom, a suitable dividing-arm for regulating the width of the swath to be gathered by said machine, and a suitable mechanism for raising or lowering said revolving frame together with said dividing-arm, substantially as described.

15. In a machine of the class described, the combination with a frame suitably mounted upon carrying-wheels, a revolving frame carried by said wheeled frame, said revolving frame being provided with a series of oppo-

site gripping jaws or parts, said jaws being in position to engage the flax as said machine is moved along, means for closing said jaws to seize a gavel of flax, means for opening the same to discharge the flax therefrom, a suitable dividing-arm for regulating the width of the swath to be gathered by said machine, said gripping-jaws and dividing-arms being arranged to gather the gavel outside said carrying-wheels, whereby the carrying-wheels do not crush the standing flax, substantially as described.

16. In a flax-pulling machine, a base-frame adapted to be moved forward, a revolving frame carrying a series of oppositely-curved gripping-jaws, means for projecting said jaws outwardly and closing them to seize a gavel of flax, and means for opening said jaws to discharge said gavel therefrom and drawing the jaws inward again, spring-actuated arms projecting into the path of the gavel and adapted to gather the loose stalks and retard them until inclosed by the next set of gripping-jaws, substantially as and for the purpose set forth.

In testimony whereof I have hereunto set my hand in the presence of two subscribing witnesses.

ALFREDE C. LAMAR.
